CHECK FOR PIANO ACTIONS

Adolf Klein, New York, N. Y.

Application July 12, 1935, Serial No. 31,119

3 Claims. (Cl. 84—253)

This invention relates to the actions of upright pianos, and has especial reference to the construction and articulation of the hammer butts and their back checks, and also the means for restraining the movements of the checks, and embodies improvements over the piano action disclosed in Letters Patent of the United States No. 1,188,947, granted to me June 27, 1916.

The principal object of the invention is the provision of improvements whereby the hammer butts and their checks in an upright piano action may be economically produced and articulated, and which enables such inter-relation of the parts that repairs and replacements may be readily made should the occasion arise.

The nature of the invention and its distinguishing features and advantages will appear when the following specification is read in connection with the accompanying drawing, in which—

Figure 1 is a side elevation of a piano action selected to illustrate the invention embodied thereby;

Figure 2 is a perspective view of the back check detached;

Figure 3 is a perspective view of a hammer butt detached;

Figure 4 is an enlarged section taken on the line 4, 4 of Figure 1.

The piano action illustrated in Figure 1 comprises parts of conventional construction with the exception of the hammer butt and the back check connected therewith. The parts of the action operate in the conventional or usual manner.

As shown in the drawing, the action includes a hammer 10 mounted upon a butt 11 pivoted as at 12 upon a stationary flange 13 so that the hammer 10 may strike a musical string 14. The butt 11 is actuated by a jack 15 to throw the hammer 10 to cause it to strike the string 14 when the key 16 is struck. In accordance with the invention, the butt 11 is formed to provide recesses 17 in the opposite sides thereof respectively which will leave a reduced portion 18. Use is made of a back check 19 suitable for articulation with the butt 11. To this end, the check has spaced lugs 20 on the arm 21 thereof. These lugs 20 are disposed in the recesses 17 respectively, and a pivot 22 extends transversely through the lugs 20 and the reduced portion 18, to thus articulate the check 19 and butt 11, so that the check 19 may have pivotal movement with respect to the butt 11 in checking the rebound of the hammer 10 carried by the butt 11.

By reason of the fact that the butt 11 is recessed as shown and also by reason of the fact that the check 19 is provided with lugs 20 to establish the connection between these elements, it is possible to not only produce and articulate butts and checks at low cost, but also enables repairs and replacements of parts to be conveniently made whenever necessary.

In accordance with another feature of the invention, the butt 11 is constructed to provide a projection 23 below the reduced portion 18, so that a coil spring 24 may be employed between the butt 11 and its connected check 19. In other words, the coil spring 24 is arranged between the pad 25 and the projection 23 and the arm 21 of the check. The arm 26 of the butt 11 carries an adjusting screw 27 which bears on a pad 28 on the arm 21 of the check to retain it in the desired rearward adjusted position. The spring 24 has a normal tendency to urge the check 19 rearwardly against the screw 27 or the arm 26. The spring 24 is only strong enough to retain the check 19 seated forwardly against the screw 27 or arm 26 as the case may be, and yields readily to the rearward adjustment of the check 19 by the screw 27. The employment of a coil spring in the manner illustrated and described is of practical importance regarding the operation and facility in the incorporation of the spring.

With the parts shown in their normal relationship in Figure 1, when the key is struck, the butt 11 will be moved forwardly on its pivot 12 causing the hammer 10 to strike the string 14. The head 29 of the jack 15 will engage the shoe 30 of the check 19, thereby holding the hammer from movement in either direction when the key 16 is held depressed. When the key 16 is released, the rebound of the hammer 10 will be resisted by the back check 19 bearing against the head 29.

From the foregoing, it will be obvious there has been described a simple and practical construction of the butt and back check of a piano action whereby the mentioned objects of the invention may be attained.

I claim:

1. In a piano action, a hammer butt, a back check, the opposite sides of the butt having recesses therein, said check having spaced lugs disposed in said recesses respectively, a pivot extending through said lugs and butt, to thus pivotally connect the check with the butt, a projection on the butt, and a spring having one end engaged with said projection and the other end engaged with the check to yieldingly hold the

check in operative position with respect to the butt.

2. In a piano action, a hammer butt, a back check, the butt being formed to provide a reduced portion, said check being formed to fit against said reduced portion, a pivot extending through the check and said reduced portion, to thus pivotally connect the check with the butt, a projection on the butt below said reduced portion, and a coil spring between the projection

and check to yieldingly hold the check in operative position with respect to the butt.

3. In a piano action, a hammer butt, a back check having one end pivotally connected with said butt, said butt having a projection thereon, and a coil spring between the projection and check to yieldingly hold the check in operative position with respect to the butt. 5

ADOLF KLEIN. 10
